JACOB J. SOUDER, OF WASHINGTON, DISTRICT OF COLUMBIA.

ROOF CONSTRUCTION FOR RAILWAY-CARS.

1,200,665.

Specification of Letters Patent.

Patented Oct. 10, 1916.

Application filed January 26, 1916. Serial No. 74,804.

To all whom it may concern:

Be it known that I, JACOB J. SOUDER, (whose post-office address is 1417 F street, NW,) a citizen of the United States, residing at Washington, in the District of Columbia, have invented certain new and useful Improvements in Roof Construction for Railway-Cars; and I do hereby declare the following to be a full, clear, and exact description of the invention, such as will enable others skilled in the art to which it appertains to make and use the same.

The invention relates to improvements in metallic railway cars, and more particularly to the roof construction of the same, and to a means for securing the latter on the body of the former.

The primary object of the invention is to provide a simplified construction of the character mentioned, and one in which the means, aforesaid, admits of independent movement of the roof with respect to the body, when the car is in motion, and more particularly, when the latter is passing around a curve, whereby the usual rolling and twisting movement of the body is not transmitted to the roof, as is the case in the present practice of rigidly securing the roof to the body of the car.

Another object of the invention is to provide a sectional roof, preferably of metal, in which the several sections of the same are applied without the use of nails, screws, or solder, and which, after being assembled, may be independently removed, by reason of the nature of the securing means, without necessitating the unfastening or removal of the roof, or of any portion of the same.

With these and other objects in view, the invention resides in the certain new and useful construction and arrangement of parts as will be hereinafter more fully described, set forth in the appended claims, and illustrated in the accompanying drawing, in which:—

Figure 1 is a fragmentary vertical transverse section, of a known type of railway car construction, showing the roof positioned thereon, and the improved method of securing the latter to the body of the car, Fig. 2 is a similar view, as in Fig. 1, showing a modified form of roof supporting carline or truss construction, Fig. 3 is a fragmentary sectional detail showing one form of the improved carline construction, Fig.

4 is a view, similar to that of Fig. 3, showing the completed connection between the carline and the roofing elements supported thereby, Fig. 5 is a fragmentary sectional detail showing another form of carline construction, Fig. 6 is a fragmentary end elevation showing the finished end of a carline after being completed, as in Fig. 4, Fig. 7 is a detail view of a running board supporting block securing means in position to be fastened to the carline, the latter being shown in section. Fig. 8 is a fragmentary sectional view of a running-board supporting block, the securing means for the same, and of the carline to which the block securing means is fastened.

Reference being had to the accompanying drawing, in which similar characters of reference designate corresponding parts in the several views thereof, the numeral 10 indicates the body of a car, of usual metallic construction, but, preferably embodying an inset angular portion 11 to provide a channel or seat for the reception of the stringer or sheathing plate 12, which is secured within the channel in the usual manner.

Spaced transversely of the body, and supported at their opposite ends upon the upper faces of the stringers 12, are a plurality of carlines or trusses 13, preferably of inverted V-shape formation. Depending from and riveted, or otherwise secured, to the oppositely disposed flanges 14, of the carlines 13, and spaced inward of the ends thereof, are angular bracket elements 15, which are arranged to project under a flange 16, formed with the inset angular portion 11, of the car body, and to spacedly underlie the same. A loosely fitted bolt, or bolts, 17 is passed through the flange 16 and through each of the brackets 15, and is provided, at its free end below the under face of the latter, with a cotter pin 18, or other suitable securing element.

In the modified form of the invention, shown in Fig. 2, greater rigidity is to be had to the carline construction, aforesaid, and to the securing brackets 15, by interconnecting the latter by means of a brace or truss member 19, the opposite ends of the member 19 being riveted, or otherwise secured, to the under faces of the bracket members, and, in which case, the bolts 17 pass through and project below the under face of the brace, the latter being of angle iron, preferably, of an inverted T-shape in cross-section. Under

normal running conditions of a car embodying this method of securing the carlines in position, when suitable roofing material, or sections of such material, have been laid on the carlines in any desired manner, it is to be noted that the roof is free for a sufficient vertical movement to render it practically impossible for the transmittal thereto of the usual rolling and twisting movement of the car body, thus eliminating the destructive strains and stresses thereto, now common in the known types of car roofs, and methods of securing the same in position.

The invention, however, contemplates a specific form of carline construction, and, referring more particularly to Fig. 3, the same comprises a pair of substantially L-shaped angle members 20, disposed in reversed parallel relation, and clamping, between their vertical parallel flanges, the over-lapped edges of a folded sheet metal securing member 21, the intermediate portion of the latter being formed into a somewhat flattened loop 22, the opposite edges of which extend to either side, in a slight downward inclined position, and overlie respective horizontal flanges of the angle members 20. The vertical flanges, and the over-lapped edges of the member 21, are secured together by means of rivets 23, which are preferably counter-sunk in the faces of the said flanges. Roofing sections 24, having side flanges 25, are adapted to be inserted between each pair of carlines, and supported upon the horizontal flanges of the latter, the flanges 25, of the sections, contacting adjacent faces of the vertical flanges, and secured in such relation, by the folding down of the respective over-hanging portion of the securing member 21, as shown in Fig. 4.

In Fig. 5, a carline construction is shown, wherein the same comprises an inverted T-shaped member 26 having the opposite folded edges of a securing member 27 disposed along the opposite faces of its vertical flange 28, and secured thereto by means of rivets 29, as shown. The roofing sections 24 are supported upon the horizontal flanges, of the member 26, and secured thereon in the usual manner, aforesaid.

In Figs. 6 and 7, there is shown a preferred form of securing means for positioning running-board supporting blocks at the ridge of the roof, and the same comprises oppositely disposed clips 30, of sheet metal, adapted for engagement over the opposite edges of either the securing member 21, or the similar member 27, prior to the folding of the latter into position for securing the roofing sections 24 to the carlines, and are rigidly retained in operative position, when the said members 21 or 27 are folded into operative position, as shown in Fig. 7. The clips 30 are connected at opposite sides of

an eye-bolt 31 by means of a pin 32. These securing devices are arranged in pairs, one to either side of the ridge of the roof, to engage in grooves 33, formed in the blocks 34, and have their bolt-members 31 projected through the block to receive a securing nut 35, which preferably lies within a counter-sunk opening 36, formed in the upper face of the block. After the block is thus secured in position on the roof, suitable running-boards 37 are secured in proper position on the latter. It is to be desired that the opposite extremities 38 of the securing members 21 and 27 be bent around, or over, the outer ends of the carlines, as shown in Fig. 8, to give finish to the construction and the assembly of the roofing sections, as well as to provide an air and water-tight joint at this point.

To adapt the roof, thus provided, for use in connection with refrigerator cars, or the like, the invention contemplates the provision of a ceiling, not shown, the same to be made into a number of sections corresponding to the number of spaces between the several carlines, and each of said sections loosely supported in proper position upon the opposed horizontal flanges of the T-shaped braces or trusses 19, thus forming a dead air space, extending the length of the car, between the roof and the ceiling, and insulating the interior of the car from the effects of all external temperatures. The sections of ceiling may be of any desired and suitable construction, or made up of the tongue and groove board construction, now in common use for such purpose. It is to be noted of this arrangement, that the ceiling sections, in no way, interfere with the desired independent movement of the roof in its adjustment on the body of the car, for the purpose as hereinbefore set forth.

It is to be understood that various changes in the detail construction and arrangement of the parts of the invention may be resorted to without departing from the spirit and scope of the same.

Having thus fully described the invention, what is claimed, is:—

1. A railway car comprising a body, and a roof, of unitary construction, mounted for vertical movement relative to the body.
2. A railway car comprising a body, and a roof, of unitary metallic construction, mounted for vertical movement relative to the body.
3. A railway car comprising a metallic body, and a roof, of unitary construction, mounted for vertical movement relative to the body.
4. A railway car comprising a metallic body, and a roof, of unitary metallic construction, mounted for vertical movement relative to the body.

5. A railway car comprising a body, and a sectional roof, the sections of the latter being secured together to provide a unitary construction, mounted for vertical movement relative to the body.
6. A railway car comprising a body, carlines spaced transversely of said body and loosely secured for vertical movement with respect thereto, and roofing elements secured to said carlines.
7. A railway car comprising a body, carlines spaced transversely of said body and loosely secured for vertical movement with respect thereto, and sectional roofing elements rigidly secured to said carlines.
8. A railway car comprising a body, carlines spaced transversely of said body, means for securing said carlines to said body for vertical movement with respect thereto, and sectional roofing elements interposed between said carlines and secured rigidly thereto.
9. A railway car comprising a metallic body, carlines spaced transversely of said body, securing brackets carried by said carlines, fastening means loosely connecting said brackets to said body, and sectional roofing elements secured to said carlines.
10. A railway car comprising a metallic body, carlines spaced transversely of said body, securing brackets carried by said carlines, securing flanges carried by said body, fastening means loosely connecting said brackets to said securing flanges, and sectional roofing elements secured to said carlines.
11. A railway car comprising a metallic body, carlines spaced transversely of said body, securing brackets spaced inwardly of the ends of said carlines, trusses connecting said brackets, securing flanges carried by said body, fastening means loosely connecting said brackets and their adjacent truss ends to said flanges, and sectional roofing elements secured to said carlines.
12. A railway car comprising a metallic body, a channel extending around the upper edges of the walls of said body, stringers carried in said channel, flanges formed with said channel, carlines spaced transversely of said body and supported on said stringers, securing brackets carried by said carlines and engaging under said flanges in spaced relation thereto, fastening means loosely connecting said brackets to said flanges, and sectional roofing elements secured to said carlines.

In testimony whereof I affix my signature.

JACOB J. SOUDER.
